UNITED STATES PATENT OFFICE

PHILIP KIRBY, OF MOUNT SAVAGE, MARYLAND, ASSIGNOR OF ONE-HALF
TO H. D. LOWERY, OF SAME PLACE.

CHURN.

SPECIFICATION forming part of Letters Patent No. 309,470, dated December 16, 1884.

Application filed March 29, 1884. (No model.)

To all whom it may concern:

Be it known that I, PHILIP KIRBY, a citizen of the United States, and a resident of Mount Savage, in the county of Alleghany and State of Maryland, have invented certain new and useful Improvements in Churns; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved churn. Fig. 2 is a side elevation of the churn with the mechanism for operating the dasher removed. Fig. 3 is a perspective view of the removable cross-piece or top-latch, and Fig. 4 is a detail view of the operating- 10 disks and handle.

Similar letters of reference indicate corresponding parts in all the figures.

My invention has relation to churning having rotary reciprocating dashers of that class in 15 which the vertical dasher-staff is operated by bands or straps fastened upon it at two different points, coiled around it in opposite directions at their point of attachment, and then fastened at their free ends to circular disks, 20 so that by operating said disks a rotary reciprocating motion will be imparted to the dasher-staff and dasher; and my improvement consists in the improved construction and combination of parts of the operating mechanism, as 25 hereinafter more fully described and claimed.

In the accompanying drawings, A denotes the churn, and B the dasher-staff, into the upper end of which is inserted a metallic stud or pin, C. D is the upper and E the lower strap, 30 both of which are of leather or other suitable material, and fastened at one end to the staff, the upper strap or band, D, being fastened to the staff just below the pin C, while the lower strap or band, E, is fastened to the staff just 35 above the cover F. The straps D and E are wound around the staff in opposite directions, one of them, D, being fastened removably at 40 d to the disk G, and the other, E, being simi-

larly fastened at e to the other disk, H. The two disks G and H are united parallel to each other by the handle I. Upon one side of the churn is a standard or upright, J, having a box, K, for the insertion of the removable pin or bolt L, which is inserted through the centers of the disks G and H, and upon which these are journaled. By drawing out this bolt and unhooking the straps D and E from their attachments to their respective disks these may readily be removed when desired. The upper end of the dasher-staff is braced 50 by the latch-piece M, one end of which has a square aperture, N, fitting upon the tenoned or reduced upper end of the upright J, and held in place thereon by the pin O. The other end has a hole, P, for the insertion of the stud or pin C in the upper end of the dasher-staff. Thus it will be seen that the staff may readily 55 be removed, whenever desired, by removing the latch-piece M, which can be done simply by withdrawing its fastening pin or bolt O 60 and unhooking the straps from their respective operating-disks.

Having thus described my invention, I claim and desire to secure by Letters Patent of the United States—

In a churn of the described class, the combination of the parallel vertical disks G H, 75 fixed on opposite sides of the handle I, and adapted to engage the operating bands or straps D E, and the post or upright J, provided with the box or bearing K, and disposed between the parallel disks, whereby said post or upright serves both as a bearing 80 and a guide for the disks working on opposite sides thereof, substantially as shown and set 85 forth.

In testimony that I claim the foregoing as my own I have hereunto affixed my signature in presence of two witnesses.

PHILIP X KIRBY.
his
mark.
